UNITED STATES PATENT OFFICE

WILLIAM A. RUBAZEWICZ, OF JAMAICA, NEW YORK

COMBINED CURTAIN AND DRAPERY FIXTURE

Application filed October 6, 1928, Serial No. 310,711. Renewed May 31, 1930.

My invention relates to combined curtain and drapery fixtures and relates particularly to fixtures of this character which are capable of vertical movement within a window frame.

When draperies and curtains are fixedly attached to a window frame, the space for the admission of air at the upper portion of the window is bounded by the inner edges 19 of the draperies, the bottom of the curtain and the edge of the lowered upper window sash.

As draperies usually cover a considerable area of a window frame they thus greatly 15 curtail the air space.

Roll curtains in order to be effective in preventing the admission of light are usually attached to the upper portion of the window frame, a position which prevents them 20 from covering the lower portion of a window sash while admitting air through a partially lowered upper sash.

The device of my invention overcomes the above described objections and presents a 25 means whereby the entire width of the upper portion of a window frame may be employed as an air-space while the lower or unopened portion of the window frame may be covered with draperies and curtains, if 30 desired.

A further advantage of my device is that it allows the positioning and arranging of draperies and curtains while standing upon the room floor thus overcoming the difficulties and dangers incident to such positioning 35 and arranging from step ladders and similar devices.

Another advantage is that the window glass may be much more readily cleaned than 40 is possible with fixed drapery and curtain fixtures.

Other advantages of my device will be evident upon a consideration of my specification and its accompanying drawings.

In the accompanying drawings illustrating modified forms of the device of my invention similar parts are designated by similar numerals.

Figure 1 is a front view of a window frame

showing the raised position of the draperies and curtains carried by my device.

Figure 2 is a front view of my device in lowered position.

Figure 3 is a front view of one form of 55 my device with draperies removed.

Figure 4 is a section through the line 4-4 of Figure 3.

Figure 5 is a section through the line 5-5 of Figure 3.

Figure 6 is a section through the line 6-6 of Figure 3.

Figure 7 is a section through the line 7-7 of Figure 3.

Figure 8 is a fragmentary vertical section 65 of one side of a modified form of my device.

The particular form of the device of my invention illustrated in Figures 1 to 7 inclusive, of the accompanying drawings comprises two similar guide rods 10 and 11, the lower end of each of which is attached to the lower element 12 of a window frame by means of a plate 13 which is fixedly attached to the frame 12 by means of a screw 14, the plate 13 abutting upon a side member 15 or 16 of the window frame. Each plate 13 has an opening therein to receive a supporting rod. The guide rods 10 and 11 are attached to the upper window frame 17 by plates 18 and 18, which are similar to the lower plates 13 and 13. 75

The slidably movable operating portion of my device comprises two flat bars 19 and 20, the lower portion 21 of each being bent outwardly of the window frame and having an 85 opening therein through which one of the rods 10 or 11 is passed. Each bar 19 and 20 has an inwardly extended abutting lapped portion 22 having a hole through which a rod 10 or 11 is passed. The upper portion of each bar 19 and 20 has an inwardly 23 and upwardly 24 extended portion, the member 23 having a hole therein through which a rod 10 or 11 is passed. The flat bars 19 and 20 are thus vertically movable along the rods 10 and 11. 90

The bars 19 and 20 are connected by a cross-bar which consists of a bar 25 fixedly attached to one member 24 and a bar 26 fixedly attached to the other member 24, the bars 25 and 100

26 overlap, bar 25 having extended pins 27, 27 passing through and horizontally movable within elongated openings 28, 28 in bar 26. The vertical bars 19 and 20 can thus be spaced 5 to accommodate the device to window frames of different widths.

A block of wood 29 is attached to each end portion of the cross-bars 25 and 26 to which suitable drapery supports 30 and 31 are attached carrying the depending draperies 32 and 33.

Fixedly attached to the cross-bars 25 and 26 are dependent curtain-roller holders 34 and 35, carrying a spring curtain roller 15 upon which a curtain 36 is wound.

A locking means for maintaining the movable operating elements at any desired position upon the rods 10 and 11 comprises an element 37 fixedly attached to the flat bar 19 and 20 having a threaded opening therein to receive the threaded pin 38 capable of being abutted upon the rod 10.

The window frame carries the vertically movable upper window sash 39 and the vertically movable lower window sash 40.

The modified form of my device shown in Figure 8 is similar to that previously illustrated and described except that the vertically movable bar comprises a bar 40 having an inwardly extended extremity 41 through which the rod 10 is passed and the two outwardly extended abutting lapped portions 42 and 43 through which the rod 10 is passed.

The operation of my device is as follows:—

35 The screw 38 is released from contact with the rod 10 and the device moved upwardly or downwardly to the desired position and the screw 38 moved inwardly to abut upon the rod 10, thus holding the device in position, the draperies 33, 33 and the curtain 36 moving vertically with the device.

When the operating device is in its uppermost position, the curtain 36 rolled up and the upper and lower window sashes positioned as in Figure 1, the only space for the admission of air is the space A above the sash 40 and the inner edges of the draperies 33 and 33. If, however, the device be lowered to the position shown in Figure 2, the space 45 for the admission of air has been increased to space B.

Further, it will be noted that if in Figure 1 the curtain 36 were drawn down to the top of sash 40 there would be no air space, while 55 if the device were then lowered to the position shown in Figure 2, there would be the air space B.

It will also be noted that if the curtain 36 in Figure 1 were drawn to the bottom of the 60 window frame in order to prevent light from entering the lower sash there would be no air space, while in the position shown in Figure 2 there would be air space B.

The device when in lowered position allows 65 of the hanging and arrangement of the dra-

peries and curtains from the floor of the rooms.

My device, therefore, possesses many attributes of convenience and value in the manipulation of window curtains and draperies.

I do not limit myself to the particular size, shape, number or arrangement of parts as illustrated and described as these are given simply as a means for clearly describing the 75 device of my invention.

What I claim is:—

In a combined curtain and drapery fixture, in combination, a pair of vertical guide rods adapted to be fixedly attached to opposite 80 sides of a window frame; a pair of vertically movable flat bars each having bent overlapped guide portions, between its extremities, each said guide portions having openings through which one of the guide rods 85 passes; an extensible cross-bar connecting the upper portions of the movable bars, means for maintaining drapery fixtures carried by said cross-bars; roller-curtain carrying means carried by said movable bars below said cross-bar and means for maintaining said device in predetermined positions upon said guide rods.

Signed at New York city, in the county of New York and State of New York, this 95 3rd day of October, 1928.

WILLIAM A. RUBAZEWICZ.
